SPRING STARTER

Raymond P. Lansing, Montclair, N. J., assignor
to Eclipse Aviation Corporation, East Orange,
N. J., a corporation of New Jersey

Application February 18, 1931. Serial No. 516,774

8 Claims. (Cl. 185—41)

This invention relates to engine starting mechanism, and more particularly to a device of the spring motor type adapted for use in cranking internal combustion engines.

5 One of the objects of the invention is to provide a novel means for cranking an internal combustion engine which is so constructed that cranking energy may be stored in said means at the will of an operator and utilized thereafter at any convenient time.

Another object is to provide a novel engine starter of the type embodying a resilient member as the element in which energy is adapted to be stored. A further object is the provision of novel 15 starting mechanism particularly adapted for cranking small engines such as outboard engines for boats.

Further objects are to provide a device which is compact, light in weight, inexpensive to manufacture and readily installed on engines now in use, one which is readily adapted for manual operation, and one in which the effort required on the part of the operator for storing up energy is reduced to a minimum. The above and other 25 objects will appear more fully hereinafter in the detailed description.

One embodiment of the invention is illustrated in the accompanying drawing, but it is to be expressly understood that the drawing is for 30 purposes of illustration only and is not to be designed as a definition of the limits of the invention, reference being had for this purpose to the appended claims.

In the drawing:

35 Fig. 1 is an axial section of one embodiment of the invention; and

Fig. 2 is a detail view, partly in section, taken along the line 2—2 of Fig. 1.

In the form shown, the structure of the present 40 invention preferably includes a housing 3 adapted to be secured in any suitable manner to the engine to be started. It will be understood that if the structure of the invention is applied to an outboard engine for boats, housing 3 will occupy 45 a vertical or upright position and will be rigidly mounted above the flywheel and substantially coaxial therewith.

Since the details of construction of the engine per se form no part of the present invention, it 50 will be sufficient for a clear understanding of the latter to point out that a clutch member 4, which may be of the jaw type, is drivably connected to a suitable member of the engine to be started such as a flywheel, crankshaft, etc.

55 Housing 3 is provided intermediate its ends

with a transversely-extending wall or partition 5 and at its outer end with a closure plate 6 which may be secured in any suitable manner to said housing as by means of screws (not shown). Extending centrally through wall 5 and plate 6 is a shaft 7 which is rotatably mounted in partition 5 and cover plate 6.

Suitable means are operatively connected to shaft 7 for engaging the rotatable member of the engine to be started, said means being so constituted that, during the normal operation of the engine, the starting apparatus is disconnected from said engine. In the form shown, the inner end of shaft 7 is threaded as at 8 to receive a jaw clutch member 9 which is adapted for rotary and longitudinal movement along the threaded portion 8, and for driving engagement with member 4. Rigidly attached in any suitable manner, as by means of threads to the inner end of shaft 7, is a nut 10, the hub of which constitutes a stop for member 9 whereby longitudinal movement of the latter is positively limited and said member 9 is constrained to rotate with the shaft 7. Preferably resilient means, such as a coil spring 11, which surrounds shaft 7, is interposed between the stop nut 10 and the jaw member 9 in order to retain said member 9 in disengaged position during normal operation of the engine and to prevent creeping of said member 9.

Energy storage means, such as a suitable spring, is preferably provided for actuating 85 member 7. In the form shown, a spiral spring 12 is secured at its inner end in any convenient manner to shaft 7, while the outer end of said spring is anchored to casing 3. In the embodiment illustrated, the outer end of the spring is provided with an eye through which extends a pin 13 adapted to be inserted through openings in lugs 14 which may be formed integrally with casing 3. A cotter pin 15 may be employed for retaining pin 13 in position.

Suitable means are provided for storing energy in the resilient member 12, and, preferably, said means are so constructed that the same are normally disconnected from the resilient member. In the illustrated embodiment, shaft 7 has rigidly attached thereto, adjacent spring 12, a gear 16 adapted to be engaged by pinion 17 secured to, or integral with, a slidably and rotatably mounted shaft 18 which extends through an opening in cover plate 6 and through an opening in a lug or boss 19 rigid with casing 3. A coil spring 20 surrounds shaft 18 intermediate lug 19 and pinion 17 and is of such length that normally the pinion is yieldingly held by said spring

110

out of engagement with the gear 16, such position being indicated in dotted lines at 21. The outer end of shaft 18 carries a hand lever 22 which may be rigidly attached to said shaft or 5 detachable therefrom.

Means are provided for holding the resilient means 12 under tension after energy has been stored therein, said means being manually operable to release said resilient means whereupon 10 the stored energy is effective to operate the elements of the starter to crank the engine. In the embodiment shown, the locking and releasing means are constituted by a lever 23 pivoted intermediate its end at 24, the inner end of said 15 lever constituting a pawl 25 for engagement with the teeth of gear 13, a suitable opening 26 being provided in the casing 3 to permit mounting of lever 23. Attached in any suitable manner to the outwardly projecting arm of lever 23 is a 20 coil spring 27 having one end anchored to the casing as by means of a pin 28. Normally, spring 27 is effective to hold the inner end 25 of lever 23 in engagement with the teeth of gear 16 whereby stored energy may be retained in 25 resilient means 12.

In operation, lever 22 is moved downwardly or 30 to the left as viewed in Fig. 1 to mesh pinion 17 with gear 16, and thereafter said lever is rotated and is effective through said pinion and gear to rotate shaft 7 and store energy in resilient means 12, the pawl or member 23 being effective to prevent the spring 12 from unwinding in the event that the pressure is removed at any instant from lever 22. After spring 12 has been wound up, 35 i. e., after sufficient energy has been stored therein to perform the cranking operation, lever 22 is released and spring 20 is effective to move pinion 21 to non-meshing position. The energy expended in winding the spring is now available 40 at any time for cranking the engine by actuating the pawl or lever 23. Movement of the latter about its pivot in a counter-clockwise direction releases gear 16 for rotation relatively to the housing whereupon shaft 7 is rotated and 45 the inertia of member 9 is effective to move the latter along the threaded portion 8 of the shaft into driving engagement with the clutch member 4 connected to the engine. The energy in the spring is now effective to crank and start the 50 engine.

As soon as the engine starts under its own power, the clutch member 9 is automatically moved out of engagement with clutch member 4 due to the inclined teeth of said clutch members, the screw and nut action of elements 8 and 55 9, and spring 11.

There is thus provided novel engine starting mechanism of the manually operable type which 60 is simple in construction, inexpensive to manufacture and which can be readily installed on engines now in use. It will be apparent that various forms of gearing may be employed, but preferably said gearing is so constructed that the 65 connection between the lever 22 and shaft 7 is broken prior to release of the spring restraining means. Various types of restraining means may be employed and various means may be adopted for securing the spring during the winding operation, it being desirable to avoid sharp bends in the spring 12. Additionally, other forms of 70 clutches than that constituted by the jaw clutch members 4 and 9 may be substituted as will be understood by those skilled in the art. Reference will therefore be had to the appended

claims for a definition of the limits of the invention.

What is claimed is:

1. In a starter for an internal combustion engine of the type embodying a driving member adapted to move longitudinally to engage and rotate a member of the engine to be started, the combination with said driving member and engine member of resilient means for actuating said driving member in both its longitudinal and rotary movements, means for manually energizing said resilient means comprising a hand crank and a gear train interposed between said hand-crank and resilient means, means engageable with said gear train for retaining in said resilient means the energy imparted thereto by said manually operated means, and a second manually operable device for releasing said last named means to cause operative engagement between said driving and engine members. 80

2. In a device of the class described, in combination with a member to be driven, a rotatable shaft, a driving member mounted thereon for longitudinal movement into engagement with said driven member and for rotary movement therewith, means for producing such combined rotary and longitudinal movement comprising a member secured to said shaft, and in which energy is adapted to be stored, means for storing energy in said member, and means for releasing the energy thus stored at will, at any desired time thereafter. 90

3. In a device of the class described, in combination with a member to be driven, a rotatable shaft, a driving member mounted thereon for longitudinal movement into engagement with said driven member and for rotary movement therewith, means for producing such combined rotary and longitudinal movement comprising a member secured to said shaft, and in which energy is adapted to be stored, means for storing energy in said member, and means for preventing the release of the energy thus stored for any desired period. 100

4. An engine starting apparatus including a driving member adapted to engage a member of the engine to be started, and operating means therefor, said operating means comprising a rotatable shaft drivably engaging said driving member, a housing surrounding said shaft and provided with means for rotatably supporting said shaft, a coiled spring connected to said shaft at one end and to said housing at the other, means for manually rotating said shaft to wind said spring, resilient means for opposing movement of said driving member into engagement with said engine member during operation of said winding means, and means for retaining the energy thus stored in said spring until it is desired to produce engagement between said driving and engine members. 110

5. An engine starting apparatus including a driving member adapted to engage a member of the engine to be started, and operating means therefor, said operating means comprising a rotatable shaft drivably engaging said driving member, a housing surrounding said shaft and provided with means for rotatably supporting said shaft, a coiled spring connected to said shaft at one end and to said housing at the other, means for manually rotating said shaft to wind said spring, and means for opposing movement of said driving member into engagement with said engine member during operation of said winding means, said means being insufficient to 120

prevent such movement of the driving member upon release of the energy stored in said spring.

6. An engine starting apparatus including a driving member adapted to engage a member of the engine to be started, and operating means therefor, said operating means comprising a rotatable shaft drivably engaging said driving member, a housing surrounding said shaft and provided with means for rotatably supporting said shaft, a coiled spring connected to said shaft at one end and to said housing at the other, means for manually rotating said shaft to wind said spring, means for opposing movement of said driving member into engagement with said engine member during operation of said winding means, means for retaining the energy thus stored in said spring until it is desired to produce engagement between said driving and engine members, and means for releasing said maintaining means to cause movement of said driving member into engagement with said engine member by virtue of the superior force of the energy stored in said spring.

7. In a device of the class described, the combination with a rotatable shaft having a member mounted thereon for longitudinal movement relative thereto and rotary movement therewith,

means for rotating said shaft comprising a spring secured thereto at one end, and held stationarily at its other end, means for placing a stress in said spring comprising a gear connected to said shaft and a second gear normally out of engagement with said first named gear and adapted to be manually moved to engage and rotate said gear, and a second manually operated device engageable with said first named gear to control the transfer of torque from said spring to said shaft.

8. In a device of the class described, a rotatable shaft having a member threaded thereto for engagement with a member to be driven, actuating means for said shaft comprising a spring in which energy is stored for subsequent application to said shaft, manually operable means for storing energy in said spring comprising a member normally disconnected from said spring but movable into position to energize said spring, means for suddenly applying the energy thus stored in said spring to said shaft to cause engagement of the driving member with the engine member, and means operable upon the release of said manually operated means to disestablish operative connection between said spring and energizing means.
